UNITED STATES PATENT OFFICE.

JOHN B. LASURE, OF LEBO, KANSAS.

CHECK-ROW-WIRE ANCHOR.

SPECIFICATION forming part of Letters Patent No. 509,913, dated December 5, 1893.

Application filed June 22, 1893. Serial No. 478,543. (No model.)

To all whom it may concern:

Be it known that I, JOHN B. LASURE, of Lebo, Coffey county, Kansas, have invented certain new and useful Improvements in Adjustable Check-Row-Wire Anchors, of which the following is a full, clear, and exact description, reference being had to the accompanying drawings, forming a part hereof.

This invention is designed for use as an anchor for check-rower wires; and relates to that class where a swinging frame or arm is employed to automatically carry the wire to a position in line with the approaching planter and my object is to produce a device of this character which is simple, strong, durable and inexpensive of construction, and easily moved from one position to another.

To the above purposes, my invention consists in certain peculiar and novel features of construction and arrangement as hereinafter described and claimed.

In order that my invention may be fully understood, I will proceed to describe it with reference to the accompanying drawings, in which—

Figure 1, represents a perspective view of a check-rower wire anchor constructed in accordance with my invention, and Fig. 2, represents a diagrammatic view to illustrate the operation of my invention when in actual service.

I will first describe the construction of the anchor and will then proceed to explain its use.

In the said drawings, 1 designates a bar of wood or metal if desired, which is preferably about two feet long. Projecting from the upper side of said bar and arranged longitudinally and centrally thereof are the loops 2 and 3, and formed vertically through said bar preferably near each end are holes or apertures 4. An approximately V-shaped frame is formed of the bar 5 and the bar 6; the bar 6 being secured a suitable distance from the outer end of the bar 5 by plates 7 or in any other suitable manner, and secured to the lower or inner end of the bars 5 and 6 are the clips or loops 8 and 9 which pivotally engage the loops 3 and 2 respectively. The outer end of the bar 5 has secured thereto by bolts or other suitable means and projecting forwardly therefrom the clip-plates 10, and secured to said plates or formed integral there-

with is the bifurcated or forked arm or extension 11. A check-rower wire, as hereinafter explained, is adapted to be secured in this bifurcated arm or extension 11, and when a strain or tension comes upon said wire as also hereinafter referred to, the frame composed of the bars 5 and 6 and which I shall herein-after designate as the wing-frame is caused to move pivotally from one side to the other.

In the operation of planting, I use two anchors designated respectively A and B constructed in accordance with my invention. The anchor A is placed at the starting end of the field between the first two rows to be planted, in such manner that the outer end of the wing-frame shall lie upon the end of first row, and the other B is placed at the opposite end of the field so that the outer end of its wing-frame shall also lie upon the first row; check-rower wire C is then connected at its opposite ends to the bifurcated arms 11 at the outer ends of said wing-frames. The planter D being operatively connected up through the wire C in the usual manner is then started from the wing-frame A along the first row and toward the wing-frame B, dropping the corn during its passage in the usual manner. The planter reaches the end of the row. The anchor B is now transferred and anchored or secured so that it shall lie between the second and third row; the outer end of the wing-frame resting at or upon the end of the second row. The planter D is again connected up to the wire and started along the second row and toward the opposite end of the wire, and when it approaches to within say, fifty feet, possibly more or less, the tension or strain upon the wire will cause the wing-frame of the anchor A having its outer end resting upon the first row, to swing or pivotally move about one hundred and eighty degrees so that its outer end shall rest upon the second row and in alignment with the approaching planter and the outer end of the wing-frame of the anchor B. The anchor A is now transferred and anchored or secured between the third and fourth rows and arranged so that the outer end of its wing-frame shall lie at or upon the third row. The planter is now connected up and moved toward the opposite end of the third row, and when it reaches, say within fifty feet, more or

less, of the anchor B, will cause the wing-frame thereof having its outer end on the second row, to swing about one hundred and eighty degrees so that its outer end shall lie 5 upon the third row and in alignment with the approaching planter and with the outer end of the wing-frame of the anchor A. This operation is repeated until all the rows have been planted.

10 It will be observed from referring to Fig. 2 that the dotted lines a, designate the wire stretching from the outer end of one wing-frame to the outer end of the other and extending diagonally across the spaces between 15 every alternate pair of rows. The unbroken or continuous lines C designate the wires when the planter is operatively connected thereto and moving from one anchor toward the other. The heavy bent or oblique portion 20 of the first wire C shows the position of said wire before the tension is sufficient to throw the wing-frame to the position shown in dotted lines c. The bent oblique portion of the second wire, or rather the first wire when in 25 its second position is shown in dotted lines at d to avoid the appearance of said portion d being a continuation of the wire C in its first position. The wire C when in its third position or over the third row also has its

bent or oblique portion d, shown in dotted 30 lines for the reason above explained. The corn-planter D of which only one is employed, is shown in three positions and as traveling in the direction indicated by the arrows to more clearly illustrate the operation.

35

From the above description, it will be seen that I have produced an anchor for check rower wires which is simple, strong, durable and inexpensive of construction.

Having thus described my invention, what 40 I claim as new, and desire to secure by Letters Patent, is—

An anchor for check-row wires, comprising a bar or portion 1, adapted to be secured to the ground, and provided with loops 2 and 3, 45 in combination with an approximately V-shaped frame, consisting of a pair of bars 5 and 6, secured together, said bars being pivotally connected also to the loops 2 and 3, and a hook or bifurcated extension carried by the 50 free or outer end of said frame, substantially as described.

In testimony whereof I affix my signature in the presence of two witnesses.

JOHN B. LASURE.
